AUTOMATIC LEAD BULLET FEEDER

Michael G. Hoyer, 65 Robertson Ave., White Plains, N.Y.

Filed July 27, 1959, Ser. No. 829,918

2 Claims. (Cl. 86—45)

This invention relates to ammunition and, more particularly, to a device for loading bullets.

Many police departments, private shooters, and the like, reload their own bullets in large quantities. Ordinarily, the hand loading of bullets consumes a considerable amount of time. It is therefore an object of the present invention to provide a lead bullet feeder assembly for reloading bullets which will substantially reduce the time and effort required to reload lead bullets.

Another object of the present invention is to provide a cam operated feeding and ramming assembly for directing lead bullets through a die block in a single operation.

An additional object of the present invention is to provide a lead bullet feeder of the type described that is completely manually operated, and which has lead bullet supply means for feeding lead bullets to the mechanism for movement toward the die block, in which position the lead bullet is forced through the die block by a ram forming a part of the mechanism.

All of the foregoing and still further objects and advantages of this invention will become apparent from a study of the following specification, taken in connection with the accompanying drawing, wherein:

FIGURE 1 is a perspective view of a lead bullet feeder unit made in accordance with the present invention;

FIGURE 2 is a fragmentary side elevational view of the assembly shown in FIGURE 1, with parts broken away;

FIGURE 3 is a fragmentary transverse cross sectional view of certain parts of the assembly in a position in which a lead bullet is being fed toward the die block;

FIGURE 4 is a view similar to FIGURE 3, showing the lead bullet being moved into proximity with the punch;

FIGURE 5 is a longitudinal cross sectional view of a lead bullet supply device forming a part of the present invention;

FIGURE 6 is a fragmentary rear view of certain parts of the assembly shown in FIGURE 1; and

FIGURE 7 is a fragmentary plan view, partly in section, of still other parts of the present invention.

Referring now to the drawing, a lead bullet feeder assembly 10 made in accordance with the present invention is shown to include a base 12 upon which a main guide block 14 with a longitudinally extending bore 16 is secured.

As is more clearly shown in FIGURES 3 and 4 of the drawing, a ram or plunger 18 is slidably supported within the longitudinal bore 16 for movement past a cavity 20 having a vertical bore in communication with the longitudinal bore 26 of a vertical lead bullet supply tube 23 that is carried by an adapter 22. A stack of lead bullets 24 are supported within the tube 23 for movement downwardly into the longitudinal bore 16 of the block 14, in the path of movement of the plunger 18 from the interior 26 of the adapter 22.

The block 14 is also provided with a vertical bore 28 that slidably receives the drive pin 30 of a ram 31. A die block 34 having a central die opening 32 of predetermined size, is positioned below the vertical bore 28 so as to receive the lead bullet 24 moved into the vertical bore 28 by the action of the plunger 18.

A mounting clamp yoke 36, secured by means of a machine screw 38 to the rear end of the block 14, clampingly engages a pair of vertical posts 40 integral with the base 12, the upper ends of which are provided with caps 41 that support a bearing member 42. This bearing member 42 rotatably supports a drive shaft 44 having a crank

2

arm 46 at one end pivotally connected to one end of a connecting link 48 that has its opposite end pivotally mounted upon a transverse pin 50 of the ram 31. Thus, in response to downward movement upon the handle 52, the link 48 is operative to drive the ram 31 downwardly to force the positioned lead bullet 24 downwardly through the die opening 32. A twin sleeve 52 is slidably carried by the posts 40 and has a bracket plate 54 extending forwardly alongside the main block 14 and connected by a pin 54' to the ram 31 to be operated by the ram. The adjacent portion of the bracket 54 is provided with a substantially S-shaped cam slot 58 that slidably receives a roller sleeve 60 mounted upon a connecting pin 62 that projects outwardly through a side slot 63 in the main block 14 from the plunger 18. Thus, the bracket 54, which is mounted by means of machine screws 56 to the twin sleeve 52 is connected for vertical movement relative to the ram 31 so as to be vertically movable there-with in response to actuation of the handle 52'.

In actual use, the lead bullets 24 are stacked within the transparent supply tube 23, whereupon a single lead bullet 24 will drop into the interior of the longitudinal bore 16 of the block 14 when the plunger 18 is in a completely retracted position. During upward movement of the handle 52', the ram 31 and drive pin 30 are raised with respect to the vertical bore 28, during which movement, the follower pin 62 is caused to move through the cam slot 58 into the forward position, illustrated in FIGURES 2 and 4, in which position, the bullet 24 is moved into the vertical bore 28 in the path of movement of the drive pin 30. Additional bullets 24 are prevented from dropping down by the plunger 18 that blocks the passage thereof into the cavity. However, as the plunger 18 is returned to its initial position, such cavity is opened to permit the next bullet 24 to drop into place. The cam and follower are so arranged that as soon as the downward movement of the drive pin 30 is commenced by the handle 52', the plunger 18 is urged toward its rearward initial position. Also, as soon as the drive pin 30 is elevated by the return movement of the handle 52', the plunger 18 moves forward to drive the next bullet 24 into the vertical bore 28 in the path of movement of the drive pin 30. Since the device is self loading by the stacked arrangement of the bullets within the tube 23, a large number of lead bullets 24 can thus be forced through the die block 34 in a continuous operation.

While this invention has been described with particular reference to the construction shown in the drawing, it is to be understood that such is not to be construed as imparting limitations upon the invention, which is best defined by the claims appended hereto.

Having thus described my invention, I claim as new and desire to secure by Letters Patent:

1. A lead bullet feeder mechanism comprising a base, a main guide block supported on said base, a die block supported on said base beneath said guide block and having a vertically-extending die opening, and lead bullet supply means extending upwardly from said main guide block, said main guide block having a vertical bore in alignment with said opening in said die block, said guide block further having a longitudinal bore extending normal to said vertical bore therein, feed means for directing a lead bullet from said lead bullet supply means through said longitudinal bore into said vertical bore and into alignment with said die opening in the die block, said feed means including a plunger operable in said longitudinal bore to so transfer the lead bullet, ram means for forcing said bullet from said vertically-extending bore in the main guide block through the die opening in the die block, means mounted on said base for operating said ram means, said feed means further including a vertically-extending

plate secured to said ram means to be operated thereby, said plate having a cam slot therein and said feed plunger having laterally-extending drive means extending into said cam slot to effect thereby the operation of said feed plunger, a pair of vertical guide posts extending upwardly from said base, said main guide block laterally abutting said vertical guide posts and a clamp yoke securing said guide block to said post, a twin sleeve slidable upon said vertical posts, said vertically-extending cam plate having a bracket connection with said twin sleeve whereby said cam plate is held against lateral displacement from said laterally-extending drive means on the feed plunger.

2. A lead bullet feed mechanism as defined in claim 1, and said means for operating the ram means including a cap fixed to the upper ends of said vertical posts, a bear-

ing member fixed to said cap, a drive shaft extending through said bearing member and having a crank handle on one end and a crank arm upon the other end overlying said ram means, a link pivotally connected to the crank arm and to the ram means.
